REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

RATCHET MECHANISM.

1,130,925.

Specification of Letters Patent.

Patented Mar. 9, 1915.

Original application filed May 7, 1907, Serial No. 372,407. Divided and this application filed April 30, 1910.
Serial No. 558,616.

To all whom it may concern:

Be it known that I, REINHOLD A. NORLING, a citizen of the United States, and a resident of the city of Aurora, county of Kane, and State of Illinois, have invented 5 certain new and useful Improvements in Ratchet Mechanism; and I do hereby declare that the following is a full, clear, and exact description thereof, reference being had to the accompanying drawings, and to the letters of reference marked thereon, which form a part of this specification.

This invention relates to improvements in ratchet mechanism and consists of the matters hereinafter described and more particularly pointed out in the appended claims.

The improved ratchet mechanism is shown herein as applied to a drilling machine constructed and arranged to drill holes located 20 in close proximity to a wall or object, in a corner formed by two walls or surfaces located at right angles with each other or between two walls or objects located closely adjacent to each other, as is often required 25 in structural iron work, engine building, ship building and the like. The said drilling machine as herein shown and described is substantially identical as to its main features with that shown and described in an 30 application filed by me on May 7th, 1907, Serial Number 372,407, "Pneumatic drills", of which the present application is a division.

In the accompanying drawings:—Figure 1 is a central vertical section of a drilling machine provided with my improved ratchet mechanism, said section being taken axially through the drill spindle. Fig. 2 is a longitudinal section, taken on line 2—2 of Fig. 40 1. Fig. 3 is a longitudinal section, taken on the indirect line 3—3 of Fig. 1. Fig. 4 is a detail section illustrating the pawl and ratchet mechanism for rotating the tool spindle. Fig. 5 is a view illustrating two pawl bearing levers and pawls carried thereby and the ratchet teeth of the drill spindle. Fig. 6 is a side elevation of one of the pawl levers. Fig. 7 is a perspective view of one of the pawls. Fig. 8 is a side 45 elevation of the drill spindle separate from its coacting parts.

As shown in said drawings, 12 designates an elongated hollow frame or casing in one end of which is mounted a drill-spindle 13 and to the opposite end of which is attached 55 the power cylinder of an engine or motor. Said casing constitutes the principal part of a crank-case for the motor, and also an inclosure and support for the bearings of the drill-spindle 13 and the mechanism by 60 which the drill spindle is operated from the motor. At one end the drill spindle 13 is provided with a socket to receive the shank of the drill, and extends through the wall of the casing, turning in a bearing 14 65 in said wall. At its opposite end said spindle engages a bearing member 15 affixed to the adjacent wall of the casing, as hereinafter described. Said spindle is also provided, within the casing or frame, with a series 70 of elongated ratchet-teeth 16 arranged parallel with the axis of the spindle and constituting part of the mechanism for driving or rotating said spindle.

The motor as herein shown has the form 75 of a two-cylinder pneumatic engine, and embraces two parallel power cylinders 17, 17, located side by side and formed in a single casting 18 having at its inner end a flange 19 by which it is bolted or otherwise 80 secured to the adjacent end of the casing or frame 12, as clearly shown in Fig. 1. The pistons 20, 20 of said motor are connected by piston rods 21, 21 and connecting rods 22, 22 with the two cranks 23, 23 of the 85 crank-shaft 24, which latter is mounted at its ends in the side walls of the frame 12. The crank-shaft 24 engages at its ends anti-friction roller bearings 26 mounted in the side walls of the frame. The said piston rods 90 having cross-heads 29 which slide in cross-head guides 30 shown in the drawings as of cylindric form. The cross-head guides are formed on plates 31 which constitute the inner cylinder heads and are attached by 95 bolts to the flange 19 on the inner end of the cylinder casting, said plates 31 and the flange 19 constituting an end wall for the end of the casing 12 adjacent to the cylinders. Said inner cylinder heads are 100 equipped with bushings 33 through which the piston rods slide.

35, 35 designate valve chambers, formed in the cylinder casting and located at the opposite sides and between said cylinders. Located in said valve chambers 35, 35 are 5 the bushings 33^a, 35^a, through which are formed the various ports leading to the cylinders and the supply passage for the motive fluid, as will hereinafter appear. Said valve chambers are open at their inner ends 10 and closed at their outer ends by the end walls 36^a, 36^a of the bushings 35^a, 35^a. Reciprocating in said valve chambers are piston valves, each designated as a whole by 15 37. Each of said piston valves is provided with two reduced parts 38, 38 which form three longitudinally separated, cylindric enlargements, by means of which, during the reciprocation of each valve, communication is afforded alternately between the inlet port 20 39 of said valve chamber, and ports 40, 41 communicating with the valve chamber and the opposite ends of the cylinders, as shown most clearly in Fig. 3.

42, 43 designate exhaust ports opening 25 into the atmosphere, one at each end of the valve chamber, and which are brought alternately into communication with the cylinder ports 40, 41 through reciprocation of the piston valves. Said valves 37 are reciprocated from eccentrics 44 on the main crank-shaft 24 through the medium of eccentric rods 45 connected at their ends respectively with eccentric straps surrounding said eccentrics 44 and with the piston valves, 30 (Fig. 3). The inlet ports 39 of the valve chambers communicate with a centrally located supply passage 47 formed in the cylinder casting connected at its outer end with a tube 48 which is connected with the cylinder casting by means of a screw-threaded nipple, as shown in Fig. 1, and through 35 which the motive fluid is supplied to the motor cylinders.

A throttle valve is located within the tube 48 for controlling the flow of the motive agent therethrough. Said valve embraces a conical valve or plug 50 adapted to engage a seat 51 formed on an annular flange within said tube. The valve member is held normally against its seat by a spring 52 surrounding the stem 53 of the valve member and interposed between the valve member and an inwardly facing shoulder of a nipple 55 which has screw-threaded engagement with the outer end of said tube. The said valve member is provided with an inward axial extension or stud 56, which engages at its inner end the outer end of a hollow plug 57 located within and having endwise sliding engagement with the tube 48. The valve member 50 is lifted from its seat through the medium of a sleeve 58 surrounding and having rotative movement on the tube 48 and confined between the inner end

of the nipple 55 and an annular exterior 65 shoulder on said tube. Said sleeve is provided with an inclined slot 59 through which extends a screw-stud 60 which has screw-threaded engagement with the hollow plug 57 before referred to. The tube 48 and its 70 surrounding sleeve constitute a handle which is grasped by one hand of the operator in using the tool. Rotation of said sleeve in one direction operates through the action of said inclined slot on the stud 60 to slide the 75 hollow plug 57 and throttle valve 50 outwardly and thereby open the valve. Said inclined slot 59 is provided at its outer end with a transverse end portion adapted to be engaged by the stud to hold the valve 80 closure in its open position. The valve and mechanism for operating the same constitute no part of the present invention and the construction and operation thereof need not be further herein described. 85

Referring now to the mechanism for transmitting motion from the crank-shaft 24 to the drill-spindle, said mechanism embraces two swinging levers 61, 62 disposed one over or at the side of the other and arranged to 90 turn or rotate about the axis of the drill-spindle, and provided each with a pawl 66 adapted to engage the ratchet teeth 16 on the drill-spindle and turn the latter, when the lever is swung or moved in one direction, 95 and to pass over said teeth when the lever is swung in a reverse or backward direction. Said levers are arranged to swing or oscillate reversely in such manner that when one of the levers is swung in a direction to rotate 100 the drill-spindle forwardly the other lever is swung or moved backwardly or retracted, each lever being moved or swung forwardly, or in a direction to rotate the spindle while the other lever is being restored to its starting point. The said reversely swinging levers are so connected with the mechanism which operates the same that the retracted lever is reversed and engages the drill spindle in a manner to turn the same forwardly 110 before the lever which is then completing its forward swing is released from the drill spindle, whereby the rotation of the drill is made continuous. The said pawl carrying levers may be pivotally supported or mounted in any suitable way in the machine frame or casing, but, as shown in the accompanying drawings, they are provided at their outer or forward ends with hubs 67 having smooth cylindric apertures which fit over 115 120 and have bearing on the toothed part of the drill-spindle.

The levers are swung or vibrated through the medium of a secondary crank-shaft 70, parallel with the main crank-shaft 24, and 125 provided with two crank-pins 71, 72 corresponding with the cranks of the main crank-shaft. The secondary crank-shaft is rota-

tively mounted at its ends in antifriction roller bearings 73, 74 mounted, one set in one side wall of the frame, and the other set in the cap or closure 25. The said secondary crank-shaft is rotated from the main crank-shaft through the medium of intermeshing gear-wheels 75 and 76 on the secondary and main crank-shafts, respectively, said gear-wheels being arranged to drive the secondary shaft at the same speed that the primary crank-shaft is driven. The said levers are provided at their inner or swinging ends with laterally separated arms 78 between which the crank-pins 71, 72 of the secondary crank-shaft operate. Said fork-arms 78 of the pawl bearing levers have smooth inner parallel bearing surfaces and the crank-pins 71, 72 of the secondary crank-shaft are provided with bearing blocks 80, 80, (each made of two halves or parts to facilitate the fitting thereof over the crank-pins) which have smooth side or lateral faces for engagement with the inner faces of the fork-arms of said pawl-bearing levers. It is obvious that the enlargement of the crank-pins of the secondary crank-shaft will produce the same effect as the bearing blocks described, but, for convenience of manufacture and to increase durability, the separate bearing blocks are preferred.

The operation of the secondary crank-shaft, acting through the pawl bearing levers and their pawls to continuously rotate the drill-spindle will be apparent from a consideration of the following, in connection with Fig. 5 of the drawings. It will be observed that the crank-pins 71 and 72 of said secondary crank-shaft are located 180 degrees from each other and each crank-pin turns, in giving the power-stroke to its associated lever, in the arc farthest away from the drill-spindle. It will be also observed that, by reason of the angularity of the bearing surfaces of the arms of each lever to a line passing through the axis of oscillation of the levers and the axis of the secondary crank-shaft, as indicated at 87 in Fig. 5, when the lever is at the extreme limit of its vibratory movement in each direction, the center of the crank-pin is not on a line at right angles to the line 87, such as is indicated by the dotted line 85 in Fig. 5, but its said center is on a line at right angles to the bearing faces of the lever, and passing through the axis of the crank-shaft, such as is indicated at 86, in said Fig. 5. In other words, the movement of the said crank-pin in giving the power-stroke to the lever, is measured by the angular distance between the line 86 and a line similarly drawn through the axis of the crank-shaft at right angles to the straight bearing faces of the other lever, and is greater than 180 degrees by an amount equal to twice the angular

distance between the lines 85 and 86. That is to say, in the power-stroke from the lower position of the lever to its upper position, the crank-pin will swing not only through 180 degrees, but through an additional angle equal to the angle between the two positions of the levers. As a consequence the crank-pin of said secondary shaft has a movement through an arc of more than 180 degrees, when, during the power-stroke of the lever, the said crank-pin carries said lever from the extreme limit of its backward stroke to the extreme limit of its forward stroke. It follows, also that the crank-pin, acting on the lever which is making its forward stroke advances said lever to a point at which the bearing faces of the lever are perpendicular to a line passing through the axes of said crank-pin and the crank-shaft, and this point is at an angular distance from the location of the crank-pin in the mid-position of the lever, equal to ninety degrees plus the angle between the lines 85 and 86 on Fig. 5. On the other hand, it will be observed that the crank-pin, when operating to retract the pawl bearing lever, reverses the direction of movement thereof at a point on a line passing through the axis of said crank-pin perpendicular to the bearing faces of said lever, so that the said lever begins its forward movement before the other lever has completed its advance or power-stroke, both levers therefore moving forward during the period of rotation of the crank-pin represented by the angle between the lines 85 and 86. Said crank-pins are shown in dotted lines in Fig. 5 as occupying positions on the dotted line 85, and in full lines as occupying positions on the full line 86. Thus it will be observed that during the time the crank-pin, acting upon the pawl bearing lever 61 which is completing its advance or power-stroke, is passing from the position indicated by the line 85 to the line 86, the said lever 61 continues to advance. During the same time the crank-pin 71, which has just retracted the pawl bearing lever 62, is passing from the position indicated by the line 85 to the position indicated by the line 86 and during this part of the rotation of the crank-pin 71, the said pawl bearing lever 62 begins its forward swing to rotate the drill-spindle.

It follows that the effective action of the crank-pins of the secondary crank-shaft upon each of said pawl bearing levers is 180 degrees plus twice the angle between the lines 85 and 86. It will therefore be seen that the action of the secondary crank-shaft through said pawl bearing levers 78 and 79 in rotating the tool spindle is a continuous one, the speed of rotation of the spindle being, of course, somewhat reduced when the levers are near the opposite limits of their vibrating movement. Inasmuch as

- each of said levers is being retracted during the greater part of the period of the power-stroke of the other lever the total movement of the pawls from one extreme position to 5 the other is but slightly greater than one-half of the angular distance between adjacent ratchet teeth, and the teeth may, therefore, be made of relatively large size and with ample bearing surfaces.
- 10 Inasmuch as the secondary crank-shaft 70 rotates in the direction indicated by the arrow in Fig. 2 and each crank-pin thereof rotates, during its power stroke, in the arc farthest away from the drill-spindle, it will 15 be seen that the greatest force of the pawl bearing devices is exerted in mid-position as shown in Fig. 2, and the greatest power is required to turn the drill-spindle, as it is then moving at its maximum speed. The 20 lever is, however, at this time exerting its greatest leverage because its associated crank-pin of the second secondary crank-shaft is at the same time operating on the part of the lever farthest from the spindle. 25 So far as the coöperation of the pawl bearing levers with the crank-shaft 70 is concerned, said crank-shaft may be rotated from any suitable source of power.
- I arrange the crank-pins of the main 30 crank-shaft at such angular distances apart that said crank-shaft exerts its greatest power to reciprocate the pawl bearing levers at a time when most needed, or at a time when the advancing pawl bearing lever is 35 in its mid-position, as shown in Fig. 2. It will be understood that a double acting engine having parallel cylinders and arranged with the crank-pins of the crank-shaft at right angles to each other gives substantially 40 uniform power throughout the full rotation of the crank-shaft and further that if the crank-pins be placed at 180 degrees apart, the power of the two pistons will be exerted simultaneously with the result, however, 45 that both crank-pins will be simultaneously on a dead center at the end of each stroke. In order to more effectively transmit power from the two pistons to the vibrating levers I arrange the crank-pins of the main crank- 50 shaft so that the pistons act on both of said crank-pins when the latter are in position requiring the greatest power to turn the same, to wit, when the crank-pins of the secondary crank-shaft are passing through 55 that part of their circular path farthest from the axis of oscillation of the levers. As shown in the accompanying drawings, the crank-pins of the main crank-shaft are placed at approximately 135 degrees apart, 60 as indicated in Figs. 2 and 3, and as a result, when the pawl bearing lever, which is making its driving or power-stroke, is at mid-position, both of the crank-pins of the main crank-shaft are in position to receive

maximum power from the pistons acting thereon. As shown in Fig. 3, the pawl bearing levers are at the limit of their vibratory movement. In this position one of the crank-pins of the main crank-shaft has just passed the dead center while the other crank-pin, is approaching its dead center. When, however, the parts are in the position shown in Fig. 2, and one of the vibratory levers is in the middle of its advance or power-stroke and the other is being retracted, one of the 75 crank-pins of the main crank-shaft will be approaching the point in its path at which the crank-shaft receives maximum power from its associated piston, while the other crank-pin will have passed such point. 80

It follows that the work of impelling each lever, during the power or driving stroke of the same, will be divided between, or participated in by, both pistons. That is to say, one of the crank-pins of the main crank-shaft will come into such position that its associated piston will exert its maximum driving power on the crank-shaft when one of the levers is approaching, and until it reaches, a point midway of its power stroke, 90 and the other crank pin will then come immediately into such position that its associated piston will exert its maximum power on the crank-shaft, to complete the power stroke of such lever. The construction described, therefore, has the advantage that the two pistons act conjointly and successively to exert maximum turning power on the crank-shaft during the time that each lever is effecting its driving or power stroke. 95 Moreover, the construction described, has the further advantage that one of the motor-shaft crank-pins will be in position for the action of its associated piston during the effective part of the stroke of said piston, 100 when the other crank pin is on its dead center.

The pawl 66 illustrated has at its free end an edge 90 for engagement with the spaces between the ratchet teeth of the drill-spindle, and at its opposite end a rounded or hinge portion 91, made integral with the body of the pawl. The two pawls are made of a combined width approximately equal to the length of the ratchet-teeth. The said 110 pawl bearing levers are provided with sockets which receive the rounded or hinge portions 91 of the pawls. The pawls are 115 spring-pressed toward the ratchet-teeth by means of a form of spring made as follows: 120 Each spring comprises an incomplete or split ring 92 surrounding the ratchet-teeth of the drill-spindle, (Fig. 4). The terminals 93 of said springs are bent outwardly from the ring-like body of the spring in parallel relation to each other and grip between them flat faced lugs 94 on the ends of the 125 pawl. The pressure exerted by said springs

serves to hold the pawls yieldingly in position to engage with the ratchet-teeth, while permitting the pawls to spring outwardly to ride backwardly over the said teeth. As 5 illustrated, said springs 92, 92 are located between the hubs of the two pawl bearing levers, in contact with each other.

The construction of the tool spindle and the manner of mounting the same in the 10 frame or casing is as described in the above named application of which this is a division. One wall of the casing or frame is provided with a bushing 100 which constitutes the bearing for the lower cylindric portion of the spindle. On the upper or inner 15 end of the said drill-spindle is mounted a ring or collar, constituting the rotative member of a thrust bearing, the non-rotative member of which consists of an annular 20 flange 103, formed on a tubular bearing member 105, which is secured in the top wall of the casing in axial alinement with the drill-spindle by means of a locking ring 102 which has screw-threaded engagement with 25 the surrounding casing wall and clamps the flange 103 against an upwardly facing shoulder on said wall. Antifriction balls 104 are interposed between the rotative ring 101 and the flange 103. The hubs of the levers 61 30 and 62 are confined between and held from movement endwise of the drill spindle by contact with the bushing 100, and the ring 101. The sleeve 105 is extended downwardly or inwardly to form an externally cylindric 35 bearing member 106 which fits within a cylindric bearing recess formed in the upper end of the drill-spindle. The bearings for holding the spindle laterally in place thus comprise the exterior bushing 100 at its 40 lower end and the interior extension 106 of the fixed sleeve 105 at its upper end. The upward end thrust of the tool-spindle is resisted by the thrust-bearing formed by the ring 101, the flange 103, and the balls 104. 45 The said tool spindle is held from downward endwise movement by an annular shoulder 107 thereon, which bears against the upper or inner end of the bushing 100.

The upper sleeve 105 is made hollow and 50 interiorly screw-threaded to receive a feed-screw 108 by which the drill is fed to its work, in a familiar manner. The said feed-screw is provided at its inner end with an axial projection 109 that extends through an 55 aperture in a transverse diaphragm or wall 110 that constitutes the stop for the drill-shank, said extension 109 being adapted to engage the drill-shank in a manner to eject the same from the tool-holder.

60 While I have shown the ratchet mechanism described herein in connection with a certain kind of drilling machine, in which its use is particularly advantageous for the reason that its construction permits of the

location of the drill-spindle closely adjacent 65 one end of the frame or casing which carries said spindle and the levers and other operating mechanism for the spindle and thereby renders possible the drilling of a hole in a wall or like part closely adjacent to a wall 70 located at right angles thereto, in a corner, or in other analogous situation, such as often occurs in structural iron work, in engine building, ship building and the like, it being evident that a hole may be drilled by the device described in a wall or like part, the center of which is as near an adjacent part or object as the distance between the center of the drill and the adjacent end of the casing or frame, it is to be understood that said 80 ratchet mechanism may be applied to other machines than drills.

I claim as my invention:—

1. In combination, a spindle, two reversely swinging, spindle-actuating levers mounted 85 concentrically with said spindle and a crank-shaft arranged parallel with the spindle and having two crank-pins located at 180° apart and severally engaging said levers, said parts being so arranged that each driving 90 stroke of each lever is effected in the movement of the crank-pin engaged therewith through the part of its path remote from the spindle and through an angular distance of more than 180° and means affording driving 95 connection between each of said levers and the spindle acting to effect driving engagement of the spindle with the lever at the end of each backward stroke of the lever and give turning movement to the spindle with 100 the lever through an angular distance equal to that of the full stroke of the lever and to also effect the release of the spindle from the lever during each backward stroke of the lever, whereby the turning movement of the 105 spindle through the action of one lever begins before the turning movement of the said spindle through the action of the other lever ceases and continuous motion is imparted to said spindle. 110

2. In combination, a rotative spindle, two reversely swinging, spindle-actuating levers mounted concentrically with said spindle, said spindle and levers being provided with coacting pawls and ratchet teeth, and a 115 crank-shaft arranged parallel with the spindle and having two crank-pins located at 180° apart and severally engaging said levers, said parts being so arranged that the driving stroke of each lever takes place in 120 the movement of the crank-pin engaged therewith through the part of its path remote from the spindle and through an angular distance of more than 180°, said ratchet teeth being spaced at angular distances 125 apart equal to the total throw of the levers, so that each pawl will come into driving engagement with one of the ratchet teeth at

the end of each backward stroke of the lever and will give turning movement to the spindle throughout the full length of each driving stroke of the lever, and the turning movement of the spindle with one lever will begin before its turning movement with the other lever ceases.

5 In testimony, that I claim the foregoing

Copies of this patent may be obtained for five cents each, by addressing the "Commissioner of Patents, Washington, D. C."

as my invention I affix my signature in the presence of two witnesses, this 28 day of 10 April, A. D. 1910.

REINHOLD A. NORLING.
